UNITED STATES PATENT OFFICE.

CHARLES H. RUTHERFORD AND CHAUNCEY TOWNSEND, OF JEROME, ARIZONA.

SMOKELESS HEATER.

Application filed August 4, 1922. Serial No. 579,630.

To all whom it may concern:

Be it known that we, CHARLES H. RUTHERFORD and CHAUNCEY TOWNSEND, citizens of the United States, and residents 5 of Jerome, county of Yavapai, State of Arizona, have invented a new and useful Smokeless Heater, of which the following is a specification.

The present invention relates to improvements in heaters and is principally intended for heating orchards. The principal object of the invention is to provide an orchard heater of the character described that will emit practically no smoke. Orchard heating 10 is done at the present time principally by means of open fires or by the well known smudge pots, both of which means emit large amounts of smoke and thereby dirty the leaves of the trees rendering the trees 15 unsightly and also interfering with the proper function of the leaves as the breathing organs of the trees. It is proposed in the present invention to provide means for heating an orchard that will be substantially smokeless.

With this object in view we have shown the preferred form of our invention in the accompanying drawing in which:

Figure 1 represents a front elevation of 30 our heater and

Figure 2 represents a vertical section through the same. While only one form of the invention is shown in the drawings and described in the specification, we wish to 35 have it understood that various changes or modifications may be made within the scope of the claims hereto attached without departing from the spirit of the invention.

Our heater 1 comprises a preferably cylindrical housing 2 covered by the plate 3, the flange 4 of which engages the upper marginal part of the housing. In the lower portion of the housing a grate 6 rests on an annular angle iron 7 secured to the wall 40 of the housing by any suitable means as by the rivets 8. The housing is divided into two parts by means of a conical plate 9 having a central opening 11 and being provided with an upturned flange 12 adapted 45 to engage and to be secured to the wall of the housing. The portion 13 underneath this conical plate constitutes the fire box and the portion 14 above the plate forms the smoke chamber.

55 To the outside of the housing is secured

a vertical support 16 for a water reservoir 17 which rests on the platform 18 held in place by means of a bracket 19. A pipe 21 connects the bottom of the reservoir with the inside of the smoke chamber and its port area can be controlled by means of a valve 22. Pipes 23 are supported in the cover plate 60 3 and extend downwardly to within a few inches of the conical plate 9 and upwardly to any desired height.

65 A door 24 is provided at a suitable height for the fire box and air is admitted to the fire box through a lower door 26.

The operation of the device is as follows. 70 The fire on the grate heats the conical plate 9 and the smoke from the fire is discharged into the smoke chamber 14. Simultaneously, water is admitted through the pipe 21 from the reservoir 17 and drops on the conical plate 9 where it is converted immediately into steam. The latter absorbs the smoke in the smoke chamber and the product is carried off through the pipes 23 to heat the surrounding air sufficiently to prevent the frost from damaging the trees or 75 the fruit on the same.

We claim:

1. In a smokeless heater, a fire box, a smoke chamber mounted thereabove, a smoke discharge into said chamber, means 80 for dripping water into the chamber creating steam in the same adapted to absorb the smoke, and draft means for guiding the products of combustion outward.

2. In a smokeless heater, a fire box, a smoke chamber mounted thereabove, a smoke discharge into the chamber, means for dripping water into the chamber creating steam in the same adapted to absorb the smoke, and a pipe leading into the chamber 90 into close proximity to the top of the fire box for guiding the products of combustion outward.

3. In a smokeless heater, a fire box having a conical top with a central opening, a smoke chamber mounted thereabove adapted to receive the smoke, means for dripping water into the chamber creating steam in the same adapted to absorb the smoke and draft means for guiding the products 100 of combustion outward.

4. In a smokeless heater, a fire box having a conical top with a central opening, a smoke chamber mounted thereabove adapted to receive the smoke, a supply of water 105

mounted above the heater having a pipe communication with the inside of the chamber allowing water to be dropped on the top of the firebox for creating steam in the chamber adapted to absorb the smoke and draft means for guiding the products of combustion outward.

5 5. In a smokeless heater, a fire box having a conical top with a central opening and an upwardly curved marginal flange, a smoke chamber mounted thereabove adapted to receive the smoke, a supply of water mounted above the heater having a pipe communication with the inside of the chamber allowing water to be dropped on the top of the firebox for creating steam in the chamber adapted to absorb the smoke and

draft means for guiding the products of combustion outward.

6. In a smokeless heater, a fire box having a conical top with a central opening and an upwardly curved marginal flange, a smoke chamber mounted thereabove adapted to receive the smoke, a supply of water mounted above the heater having a pipe communication with the inside of the chamber allowing water to be dropped on the top of the firebox for creating steam in the chamber adapted to absorb the smoke and a pipe leading into the chamber into close proximity to the top of the firebox for guiding the products of combustion outward.

CHARLES H. RUTHERFORD.
CHAUNCEY TOWNSEND.
